Primary Examiner — Marianne Pandozzi(74) *Attorney, Agent, or Firm* — Keeley DeAngelo LLP**CLAIM**

The ornamental design for a beer dispenser, as shown and described.

DESCRIPTION

FIG. 1 is a front left perspective view of a beer dispenser showing our new design;

FIG. 2 is a rear right perspective view of a beer dispenser; FIG. 3 is a front plan view in elevation of the beer dispenser of FIGS. 1 and 2;

FIG. 4 is a side view in elevation of the beer dispenser of FIGS. 1 and 2 as seen from the right-hand side thereof; FIG. 5 is a rear view in elevation of the beer dispenser of FIGS. 1 and 2;

FIG. 6 is a side view in elevation of the beer dispenser of FIGS. 1 and 2 as seen from the left-hand side thereof;

FIG. 7 is a top plan view of the beer dispenser of FIGS. 1 and 2; and,

FIG. 8 is a bottom plan view of the beer dispenser of FIGS. 1 and 2.

The broken lines in the drawing depict portions of the beer dispenser that form no part of the claimed design.

1 Claim, 8 Drawing Sheets(56)
